US00D621708S

(12) United States Design Patent
Thomas et al.

(10) Patent No.: US D621,708 S
(b4) Date of Patent: * Aug. 17, 2010

(54) JAR

(75) Inventors: Stacy Alycia Thomas, Chicago, IL (US);
Patty Hing Yan Tsang, Guangzhou (CN); Dongpo Huang, Beijing (CN);
Timothy Lee Tyler, Cincinnati, OH (US); Chaohang Deng, Guangzhou (CN)

(73) Assignee: The Procter & Gamble Company, Cincinnati, OH (US)

() Term: 14 Years

(21) Appl. No.: 29/308,534

(22) Filed: Jun. 20, 2008

(51) LOC (9) Cl. 09-01

(52) U.S. Cl. D9/500

(58) Field of Classification D9/500,
D9/502-504, 516, 549, 558, 686, 688-691;
D28/82, 91; 215/379, 381-382; 220/660,
220/662, 665, 669-673, 675

See application file for complete search history.

CLAIM

The ornamental design for jar, as shown and described.

DESCRIPTION

FIG. 1 is a perspective view of jar, embodying our new design;

FIG. 2 is a front view thereof;

FIG. 3 is a back view thereof;

FIG. 4 is a right side view thereof;

FIG. 5 is a left side view thereof;

FIG. 6 is a top plan view thereof; and,

FIG. 7 is a bottom plan view thereof.

The broken lines shown in the drawings are for illustrative purposes only and form no part of the claimed design.

1 Claim, 4 Drawing Sheets
